(57) **CLAIM**

The ornamental design for a hair growth cap, as shown and described.

DESCRIPTION

FIG. 1 is a first front, left, top, perspective view of a hair growth cap showing my new design;

FIG. 2 is a second rear, right, bottom, perspective view thereof;

FIG. 3 is a third rear, left, bottom, perspective view thereof;

FIG. 4 is a front view of FIG. 1;

FIG. 5 is a rear view of FIG. 1;

FIG. 6 is a left side view of FIG. 1;

FIG. 7 is a right side view of FIG. 1;

FIG. 8 is a top plan view of FIG. 1;

FIG. 9 is a bottom plan view of FIG. 1;

FIG. 10 is an enlarged view of a portion of FIG. 1; and,

FIG. 11 is an enlarged view of a portion of FIG. 3.

The dashed lines in the drawings depict portions of the hair growth cap that form no part of the claimed design. The dot-dash broken lines depict the bounds of the enlarged views that form no part thereof.

1 Claim, 11 Drawing Sheets
